UNITED STATES PATENT OFFICE

2,678,477

COMPOSITE WINDOW STRUCTURE

Joseph J. Russell, Ottawa, Ontario, Canada

Application July 11, 1952, Serial No. 298,382

13 Claims. (Cl. 20—52,2)

1

This invention relates to composite window structures.

An object of the present invention is to provide a self-contained window sash assembly having incorporated therein a balancing mechanism, such assembly being arranged for convenient insertion in, and removal from, a window frame as a composite unit.

Another object is to provide a combination window structure having a frame of simple and convenient manufacture, and a plurality of sash assemblies mounted in the frame for convenient removal therefrom, each said assembly having a balancing mechanism incorporated therein.

A further object is to provide a combination window structure of the type referred to, each said assembly being swingable laterally with respect to the frame to permit ready access thereto for cleaning or like purposes.

Other objects, details and advantages of the invention will become apparent as this description proceeds with respect to the accompanying drawings, in which

Figure 1 is a front elevation of a window structure in accordance with the invention.

Figure 2 is a transverse sectional view of the window.

Figure 3 is a longitudinal sectional view of the window.

Figure 4 is a partial detail view of a bar associated with the balancing mechanism.

Figure 5 is a partial transverse sectional view of a modified form of sash.

Figure 6 is an enlarged sectional detail view showing mounting of a glass sheet in the sash, and

Figure 7 is a perspective view of a sash assembly unit.

Referring to the drawings, 1 is a window frame, preferably of wood construction, 2 and 3 upper and lower sash assemblies, and 4 and 5 upper and lower storm sash assemblies.

Each sash assembly is of substantially identical construction and comprises metal side rails 6 and 7 and top and bottom rails 8 and 9. Each rail has an inner channel 10 in which is mounted a resilient or like glazing channel 11 to receive the glass panel 12. Each side rail has a rectangular opening 13 extending longitudinally therethrough, and each of top and bottom rails 8 and 9 has an opening 14 extending longitudinally therethrough and registering with a respective opening 13. Such openings 13 and 14 receive a corner angle member 15 at each corner of the sash for securing the rails together.

2

Rails 6 and 7 are arranged to slide in complementary grooves 6a and 7a in jambs 1a of frame 1 and means are provided for permitting convenient mounting of the sash assembly as a unit in the frame by easy insertion of the rails 6 and 7 into grooves 6a and 7a and similar convenient removal of the sash assembly from the frame by withdrawal of the rails 6 and 7 from grooves 6a and 7a. This is accomplished by providing rail 7 with yielding engagement with the frame. As shown, therefore, rail 7 comprises a side member 16 proper, in which is located the glazing channels 10 and 11 and which is fixed to top and bottom rails by the corner members 15, and a channel-shaped member 17, substantially coextensive in length with member 16 and having its side walls engaging and overlapping the sides of member 16, as clearly shown in Figure 2. Means yieldingly urging member 17 outwardly from member

16 and into engagement with frame 1 comprises a plurality of preferably elliptic springs 18 interposed between the edge of member 16 and the opposing wall 19 of member 17. Member 16 may be recessed at 20 to receive the apex of the

spring 18.

Means for retaining member 17 on member 16 while permitting limited outward movement of member 17 under the action of springs 18 comprises a plurality of pairs of small pins 21 fixed to the sides of member 16 and extending through respective complementary slots 22 in the side walls of member 17. A cover for each pair of pins and slots is preferably provided and may comprise a U-shaped spring clip 23 embracing the channel member 17 and extending over the pins and slots. The ends of clip 23 are inturned at 24 to engage the edges of the side walls of member 17.

It will thus be apparent that each sash assembly may be laterally compressed by applying a manual force to the sash in a direction towards groove 7a, whereupon telescopic movement of members 16 and 17 will occur against action of springs 18 with resultant withdrawal of rail 6 from groove 6a. The latter side of the sash assembly may then be swung outwardly from frame 1 (the sash having been raised sufficiently to clear sill 25 of the frame), and the entire assembly then withdrawn from groove 7a and the frame.

A balancing mechanism 26 is incorporated in each side rail 6 and 7. To this end, rail 6 has a cylindrical opening 27 extending longitudinally therethrough, rails 8 and 9 also having respective registering openings 28 and 29, to provide a continuous cylindrical opening 30 extending completely through the sash from top to bot-

tom. Rail 7 also has a cylindrical opening 31 extending longitudinally therethrough, such opening being preferably provided in the channel member 17, as shown in Figures 1 and 2.

Removably mounted in each opening 30 and 31 is a rod 32 and a coil spring 33 sleeved thereon. The lower end of spring 33 is arranged for support upon the sill 25 of frame 1 and the upper end bears upon a fixed portion of the sash which, as shown in respect of opening 30, comprises a lateral projection 34 carried by the upper corner member 15 and which projects into the upper end portion of opening 30. In respect of opening 31, a cover plate 35 may be fixed to the top of member 17, such plate having a shoulder 36 depending into opening 31 and providing a seating surface for the upper end of spring 33.

Preferably the spring 33 and rod 32 are enclosed within a tubular housing 37. The lower ends of rod 32, spring 33, and housing 37 are seated upon the sill 25 in proper assembled relation by suitable means which preferably comprises an inturned flange 38 on housing 37 and upon which the lower end of spring 33 seats, and a shoulder or disc 39 fixed to the end of rod 32 and bearing upon the end of housing 37. Disc 39 may be countersunk in the sill, as shown, and pressure of the spring upon the ends of the housing and rod maintains the latter in fixed seating relation on the sill.

The length of each rod 32 is slightly greater than the height of the sash. Thus, as shown in Figure 1, in respect of lower sash 3, and in the closed position of such sash 3, the rods extend completely through the openings 30 and 31 and protrude a slight distance above the top of the sash. This distance may be, for instance, of the order of one to four inches and need be only sufficient to enable the sash to be raised a sufficient distance above the sill to clear the latter. However, for a reason which will later appear, the rods 32 in the spring-loaded sash rails 7 are preferably slightly longer (about two inches) than the rods 32 in the other rails 6.

Means are provided for fastening the balancing mechanisms to each sash when it is desired to remove the sash assembly from the frame whereby the balancing mechanisms will be retained in properly assembled relation to the sash, and whereby the entire sash assembly may be removed from and inserted in the frame as a unit. Such means preferably comprises a separate end section 40 (preferably tapered as shown) pivoted to the end of rod 32 at 41, such section being axially recessed to receive a spring-pressed ball 42 arranged to normally retain section 40 in axial alignment with rod 32. However, section 40 may be swung to a position at right angles to rod 32, as shown in Figures 4 and 7, ball 42 engaging a complementary recess 43 in the end of rod 32 to releasably retain section 40 in such position. It will thus be apparent that, prior to removal of a sash assembly from the frame 1, it is merely necessary to swing sections 40 into right angular relation with rods 32 whereby, on removal of the sash assembly, as shown in Figure 7, the sections 40 will rest upon the top rail 8 to prevent dropping of the balancing mechanisms out of openings 30 and 31.

The invention also contemplates the provision of means permitting lateral swinging movement of each sash assembly relatively to frame 1, without complete removal of the sash assembly from the frame, for cleaning or like purposes. To this end, there is provided a pair of bars 44 piv-

totally mounted at 45 on frame 1 at a point located between the pairs of grooves 1a and opposite the upper end portions of adjacent rods 32 which, as previously indicated, are somewhat longer than the rods 32 in sash rails 6. Each bar 44 has a hook 46 at its free end for engagement with a respective pin 47 located laterally opposite pivot point 45 on each outer edge portion of frame 1 beyond the respective pair of grooves 1a. A spring 48 may be provided on pivot 45 to frictionally retain each bar 44 in engaging relation with a pin 47. As will be clear from Figures 2 and 3, when a bar 44 is hooked to a pin 47, it bridges a pair of grooves 1a and extends transversely of the elongated end portions of the respective pair of rods 32 to retain the latter in position in the grooves. Thus, sash rails 6 of the respective pair of sash assemblies may be withdrawn from their grooves 6 and the outer or both of such assemblies swung outwardly from the frame, as indicated at 48 in Fig. 2, to permit access to the inner faces of the glass panels for cleaning or like purposes. It will be apparent that rod 32, when locked in position by bar 44 as described, constitutes the pivot about which each sash assembly may swing.

Figure 5 illustrates a slightly modified form of spring-loaded sash rail 7, wherein the longitudinal opening 31 is provided in a member 49 which constitutes the fixed sash rail member directly connected to top and bottom rails 8 and 9. The balancing mechanism rod 32 and related parts are located in opening 31 in the manner previously described. Channel member 50 is similar in structure and mounting to member 17 but omits the opening for the balancing mechanism.

Referring to Figure 6, it is proposed to employ a glazing channel 11 of resilient plastic material such as that known under the trade name "Koroseal," and having beaded edge portions 51. On mounting of a glass panel 12 in such a glazing channel, the beaded edges 51 tend to be drawn into sealing engagement with the surfaces of the glass panel, as shown. Thus, one size of such a channel will accommodate various thicknesses of glass sheets while providing in each case effective sealing engagement.

As shown in Figure 2, the outer edge of each sash member 17 is preferably semi-circular in contour, and each groove 1a is of complementary contour, to permit ease of swinging movement of the sash assembly with respect to the frame. If desired, each such edge of sash member 17 may be provided with a longitudinally extending rib 52 arranged to fit into a complementary recess 53 in the frame to provide added weatherproofing engagement of the sash with the frame.

It will be apparent that, because of the spring-loaded nature of sash rail 7, a most effective weatherproofing engagement of the sash assembly with the frame is provided.

A suitable screen 54 may be incorporated in the window structure and, as shown is mounted in frame 1 adjacent the outer face of the window. It will be apparent that, in the structure described, ready access to the screen for removal or movement thereof, as desired, is possible from the inside of the window by appropriate sliding movement of the various sash assemblies.

The upper and lower sash assemblies are provided with any suitable type of meeting rail elements 55 and 56, an appropriate locking means 57, and raising and lowering flanges 58 and 59.

It will be apparent that the degree of compression of springs 33 will be chosen to provide effective and satisfactory balancing of the sash in question. It will also be apparent that the degree of compression of the spring in the upper sash assemblies will vary somewhat from that in the lower sash assemblies.

It will be observed that, since no part of the balancing mechanism is incorporated in the frame, it is of very simple and inexpensive manufacture, the jambs being merely provided with the usual sash receiving grooves.

What is claimed is:

1. A self-contained window sash assembly comprising top, bottom and side rails, each of said side rails having an opening extending longitudinally therethrough, and a balancing mechanism extending into each of said openings and comprising a detached rod freely slideable in one direction through said opening and a detached spring freely sleeved thereon and freely slideable with said rod in said one direction, one of said rails having a shoulder thereon engaged by said spring and restraining free sliding movement of said rod and spring in the other direction through said opening.

2. A self-contained window sash assembly comprising top, bottom and side rails, each of said side rails having an opening extending longitudinally therethrough, and a balancing mechanism extending into each of the openings and comprising a detached rod freely slideable in one direction through said opening, a detached spring sleeved on the rod, a shoulder fixed to the side rail and freely engaging one end of the spring, and a shoulder fixed to the rod and freely supporting the other end of the spring, said spring being freely slideable in said one direction with said rod through said opening and restraining movement of said rod in the other direction through said opening.

3. A self-contained window sash assembly comprising top, bottom and side rails, each of said side rails having an opening extending longitudinally therethrough, and a balancing mechanism extending into each of the openings and comprising a detached rod freely slideable in one direction through said opening, a spring sleeved upon the rod, a shoulder fixed to the side rail and extending into said opening to constitute a seat for one end of the spring, and a shoulder fixed to the rod and constituting a support for the other end of the spring, said spring being in unattached relation to said rails, rod and shoulders and being freely slideable in said one direction with said rod through said opening, and said spring restraining movement of said rod in the other direction.

4. A self-contained window sash assembly as defined in claim 3, including latch means for temporarily securing each of said rods to the sash assembly when in non-operative position to arrest said free sliding movement of the rod and spring.

5. A self-contained window sash assembly comprising top, bottom and side rails, one of said side rails being laterally yieldable to facilitate insertion of said assembly in and removal from a window frame, each of said side rails having an opening extending longitudinally therethrough, and a balancing mechanism extending into each of said openings, said balancing mechanism comprising a detached rod freely slideable in one direction through said opening, a coil spring sleeved freely upon the rod, a shoulder fixed to

the side rail and extending into said opening to constitute a seat for one end of the spring, and a tubular housing for the spring having an in-turned flange at one end engaged by the other end of the spring, said rod having a shoulder at one end for engagement by said flanged end of the housing, said spring and housing being in unattached relation to said rails and freely slideable in said one direction with said rod through said opening.

6. A window sash assembly as defined in claim 5, including a member pivoted to the other end of said rod, means normally holding said member in alignment with the rod, said member being swingable into angular relation with the rod for engagement with said top rail to constitute means for temporarily latching said balancing mechanism to the assembly when the latter is in non-operative position.

7. A self-contained window sash assembly comprising top, bottom and side rails, each of said side rails having an opening extending longitudinally therethrough, and a balancing mechanism extending into each of said openings, each of said balancing mechanisms comprising a detached rod freely slideable in one direction through said opening, a detached coil spring sleeved upon the rod and freely slideable with said rod in said one direction, one of said rails having a shoulder thereon engaged by said spring and restraining free sliding movement of said rod and spring in the other direction through said opening, one of said side rails comprising a member fixed to said top and bottom rails and a second member mounted on the first member for relative lateral movement therewith, and resilient means urging said second member laterally outwardly from the first member.

8. A window sash assembly as defined in claim 7, said opening in said last-mentioned side rail being located in said second member.

9. A window sash assembly as defined in claim 7, said opening in said last-mentioned side rail being located in said first member.

10. A window structure comprising a frame having a sill and jambs, said jambs having therein a plurality of complementary pairs of sash-receiving grooves, and a self-contained window sash assembly mounted in each said pair of grooves, each said assembly comprising a sash having top, bottom and side rails, and resilient means urging one of said side rails into engagement with a respective groove and permitting yielding lateral movement of the side rail to render said sash laterally compressible for removal from said grooves, each of said side rails having an opening extending longitudinally therethrough, and a balancing mechanism extending into each of said openings in unattached relation to said rails, each said balancing mechanism comprising a rod having one end supported on the sill in unattached relation thereto, a coil spring freely sleeved upon the rod, and a shoulder fixed to the side rail and extending into said opening to constitute a seat for the upper end of said spring, the lower end of said spring being supported upon said sill in unattached relation thereto.

11. A window structure as defined in claim 10, each of said rods being normally located within a respective one of said grooves and having a length somewhat greater than the height of said sash whereby the upper end of the rod protrudes above the sash when the latter is adjacent the sill, and means mounted on the frame and en-

gaging said protruding end to retain it in its respective groove, said retained rod thereby constituting a pivot about which said sash may be swung outwardly from the frame.

12. A window structure as defined in claim 10, each of said rods being normally located within a respective one of said grooves and having a length somewhat greater than the height of said sash whereby the upper end of the rod protrudes above the sash when the latter is adjacent said sill, and a bar pivotally carried by the frame adjacent said protruding ends of the rod in the resiliently urged side rail, said bar being swingable into bridging relation with the respective groove to engage said protruding end of the rod and retain it in said groove, said retained rod thereby constituting a pivot about which the sash may be swung outwardly from said frame.

13. A window structure as defined in claim 10, including a tubular housing for said spring hav-

ing an inturned flange at its lower end engaged by the lower end of the spring, said rod extending through said lower flanged end of the housing and having a shoulder thereon engaging the outer surface of said lower flanged end of the housing, said shoulder of the rod being seated upon said sill.
